METHOD OF AND APPARATUS FOR RECORD-
ING SOUND ON THE EDGE OF FILMJohn Ripley Kiel, Chicago, Ill., assignor to Ripley
Corporation, Chicago, Ill., a corporation of Illi-
nois

Application January 3, 1933, Serial No. 649,865

5 Claims. (Cl. 179—109.4)

This invention relates to a method of and apparatus for recording sound on the edge of a motion picture film, and to the sound film produced thereby.

5 An object of this invention is to provide a method of and apparatus for successfully recording sound on the edge of a motion picture film, and particularly a method which can be used on old motion picture films.

10 Another object is to provide means for adjusting the drive mechanism to correct for shrinkage of the film having sound thereon, so as to cause the film to run smoothly at the point where the reproducer pick-up is applied to the film to

15 reproduce sound therefrom, or at the point where sound is to be recorded thereon.

These and other objects, as will hereinafter appear, are accomplished by this invention which is fully described in the following specification and shown in the accompanying drawings, in which—

Figure 1 is a front elevation of the mechanism for trimming the film and for recording sound thereon;

25 Fig. 2 is an enlarged partial section on the line 2 of Fig. 1;

Fig. 3 is an enlarged detail of the roller over which the film is drawn while being trimmed;

30 Fig. 4 is a partial enlarged section on the line 4 of Fig. 1;

Fig. 5 is an enlarged detail of the film at the instant of passing under the trimming knife;

Fig. 6 is a partial enlarged section on the line 6 of Fig. 1 showing the recording mechanism;

35 Fig. 7 is an enlarged detail of the rollers for gripping the master record strip at the instant sound is recorded thereon;

Fig. 8 is a partial section on the line 8 of Fig. 7;

40 Figs. 9 and 10 are enlarged details of the film while being trimmed at the two points shown in Fig. 1;

Fig. 11 is a partial enlarged section on the line 11—11 of Fig. 7;

45 Fig. 12 is a partial plan view of Fig. 1 showing the driving mechanism;

Fig. 13 is an enlarged side elevation showing the drive sprocket of Fig. 1 with means for adjusting to accommodate for the shrinkage of the film due to age;

50 Fig. 14 is a section on the line 14—14 of Fig. 13;

Figs. 15 and 16 are partial enlarged views illustrating different positions of adjusting mechanism;

55 Fig. 17 is a partial enlarged view on the line 17 of Fig. 6 showing the recording tool in the oper-

ation of making a record on the edge of the film;

Fig. 18 is a partial transverse section of the film on the line 18 of Fig. 17;

Fig. 19 is a diagrammatic view of the motion picture camera and of the sound recording mechanism driven in synchronism;

Fig. 20 is a diagrammatic view of the mechanism for re-recording on a finished motion picture film from the master record strip;

Fig. 21 is a partial diagrammatic view of the mechanism for projecting a picture, and for reproducing sound from the edge of the same film;

Fig. 22 is a partial enlarged section on the line 22 of Fig. 21;

Fig. 23 is a reduced elevation on the line 23 of Fig. 22;

Fig. 24 is an enlarged section on the line 24 of Fig. 21; and

Fig. 25 is a longitudinal section through a pick-up device.

In general, my method of recording and reproducing comprises simultaneously taking a picture and making a master record on the edge of a separate record strip, and re-recording the sound on the edge of the finished positive motion picture film so that the picture can be projected and the sound picked up in synchronism.

My method of recording sound on the edge of a film is particularly applicable to recording on films now extant where the sound does not necessarily have to be in synchronism with the picture.

The method of recording sound on the edge of a master record strip which is preferably a film such as is used in motion picture projectors, but which for this purpose may have no emulsion thereon. This film is fed through the recording mechanism shown in Figs. 1 to 19.

Referring to Figs. 1 and 19, the master record strip A is passed through edge trimmers B and C which are preferably two or more in number, after which it passes to the recording device D, and thence to the reel F. The motor G for driving this recording mechanism and the motor H for driving the motion picture camera I are synchronous motors, and are driven from the same alternating current circuit, and both motors are under control of a single operating switch. Thus by throwing in this switch, both the motion picture camera and the sound recording mechanism are started simultaneously and are maintained in synchronism.

In order to fix the points at which the master record strip and the motion picture film start when the recording mechanism has been first

- set in motion, an operator steps in front of the camera and claps two boards together, the act and the sound being recorded simultaneously on the motion picture film and on the record strip.
- 5 Thus by setting the projector and the pick-up together at these two points on the finished film, the sound is reproduced and the picture as projected will be in synchronism.

Referring now to Fig. 1, the sound recording mechanism is mounted on a frame 30 to which is secured the synchronous motor G, which has a shaft 31 to which is keyed a worm 32 (Fig. 12) which meshes with a worm wheel 33 on a shaft 34, to which is keyed a drive sprocket 35, shown 10 enlarged in Figs. 13 to 16. The film A passing over this sprocket is drawn through the trimming and recording mechanism, as will now be described. The shaft 34 has a bevel gear 36 keyed thereon which meshes with a gear 37 on the vertical shaft 38, which in turn carries a bevel gear 39 which meshes with a gear 40 on a shaft 41. The shaft 41 serves to drive the sprockets, which 15 will later be described, which pull the film A through the trimmers and it also serves to oscillate the trimmers.

In front of the shaft 34 is a shaft 42 (Figs. 1 and 11) which carries a roller 43 having two corrugated faces 44 which are also preferably roughened slightly so as to cause them to grip 20 the film A between its face, and that of the pressure roller 45, the latter being carried upon a bell crank 46 which has an extension 47 (Figs. 7 and 11) surrounding the center of the roller 45, the bell crank being hingedly mounted at 48 and normally urged toward the roller 43 by means of a spring 49, or the like. An idler roller 50 (Fig. 8) bears upon the underside of the roller 43 and is spring-pressed, and is eccentrically mounted at 51. The roller 50 has a disk 50^a with an outwardly flared edge pressed inwardly by a spring 50^b which bears against a screw head 50^c. Thus 25 the film is held firmly against a flange 43^b on the roller 43.

Referring again to Fig. 11, the roller 43 is undercut at 43^a and is provided with the shoulder flange 43^b which forms an abutment against which the film A rests while held firmly gripped as it passes between the rollers 43 and 45. A sound recording tool 52, which will later be described, and which is carried by the recording device D, bears against the outer edge of the film at the point of maximum pressure of the roller 45. For this purpose the edge of the film, which has previously been trimmed, extends beyond the rollers a matter of .002" or .003". Before reaching this recording device, however, the film passes through one or more trimmers as B, C. To do this the film passes first around a shouldered roller 53 (Figs. 1 and 3) against which the film A is pressed by means of a roller 54 which is carried on one arm of a bell crank 55 fulcrumed at 56, and pulled down by means of a spring 57. A lever-operated cam 58 serves to lift the roller 54 against the action of the spring 57. An idler roller 59 is carried on an arm 60, and the idler roller is pressed against the film A by means of a spring 61. The film is firmly held against the back of the roller by a spring-pressed disk 59^a, similar to the disk 50^a.

70 Immediately in front of the shouldered roller 53 is a knife blade 62 which is firmly secured to an arm 63, as shown in detail in Fig. 2, the arm being pivotally mounted at 64, and held in operative position by a spring 65. The arm 63 is provided with a screw 66 whereby the distance of the

cutting edge of the blade 62 from the roller can be nicely adjusted. As the film A passes up under the blade 62 a fine shaving 67 is cut away, as shown in Fig. 5. The two arms 63 are mounted upon a reciprocating block 68 which is slidably mounted upon guides 69, 70 which are secured to the frame 30. This frame carries a stud 71 upon which is journaled a worm wheel 72 which meshes with a worm 73 on the shaft 41. On the face of the worm wheel 72 is formed a cam groove 10 74 in which operates a pin 75 which is carried by the reciprocating block 68, so that as the worm wheel 72 rotates the block 68 is propelled back and forth with a reciprocating motion, which is preferably substantially uniform in both 15 directions. A suction pipe C' draws off shavings cut from the film.

For this purpose I prefer to use a safety razor blade, and I have found that by mounting and reciprocating it in this way I am able to trim 20 between 1000 and 1500 feet of film without re-sharpening it where the blade used is of superior quality. It is necessary for good results to trim the edge, owing to the fact that the edge of the film as ordinarily used is quite rough and all of 25 its inequalities would combine with the record on the edge of the film, thereby introducing all sorts of noises unless the edge of the film were trimmed before the record was made thereon.

In Fig. 9 the edge film A' is shown quite rough. 30 As the result of the first cut the edge A² is much smoother, but is still somewhat rough. The second cut leaves a surface A³ of Fig. 10 which is very much smoother. Under some circumstances one cut would be insufficient, while under others two or even three cuts might be necessary. Each 35 cut when properly made tends to leave the surface in better condition than the one before it. Each of the cutters is provided with a driving sprocket 76, as shown in Fig. 4, which is driven from the 40 shaft 41.

In Fig. 6 is shown the recording tool and the recording device in which it is used. This device comprises a hollow iron housing 77, an iron core 78 preferably screwed therein, the housing 45 having an iron cover 79 secured thereto and loosely surrounding the free end of the core 78 so as to provide an annular air gap 80. In this gap is located a sleeve 81 about which is wound a voice coil 82 which is adapted to operate in 50 substantially the same way as the voice coils of dynamic loud speakers. The sleeve 81 is mounted upon a disk 83 which is secured to a movable member 84, the outer end of which is carried by a spring steel member 85 which is secured to a 55 spider 86 which in turn is secured to the cover 79. The sleeve 81 is guided by a fiber member 87, which in turn is secured at two opposite points to the spider 86, or the like. A magnet coil 88 surrounds the core 78, and is energized 60 by a direct current from a suitable source.

Thus it will be seen that with the magnet energized the voice coil 81 will be suspended in a strong magnetic field. I have found, however, that it is necessary to control the movement of 65 the member 84 as it has a tendency to move through too great an amplitude. For this reason I have provided a means for damping the movement of the members 84. To do this I have provided rubber pads 89, 90, or other suitable 70 damping means, on the two sides of the disk 83 while the core 78 is adjustable toward and from the pad 90 by turning the threaded core 78 in the housing 77. A lock nut 78^a is provided for locking the core in the adjusted position.

I have also found it preferable to use additional damping means consisting of rubber pads 91, 92, or other suitable material, lying on each side of a flange 93 on the member 84. Adjustment of this damping means is provided in the way of a threaded collar 94 which is screw-threaded into the center of the spider 86. The member 84 is drilled and reamed to receive a recording tool 95 which carries a recording point 96, preferably a 10 diamond ground to a point substantially as shown in Fig. 17. This point is substantially chisel-shaped, the end of the chisel being viewed in Fig. 17, and having sides which lie at an angle of about 80° to each other, the point being round- 15 ed with a radius of approximately .001".

As shown in Fig. 17, the film A is forced along beneath the recording point 96, thereby slightly propelling the edge of the film beneath the smooth face of the diamond point so as to make 20 it slightly T-shaped in cross section, as shown in Fig. 18. If at the same time a current of varying strength is passed through the voice coil 82 of the recording device, a vibratory motion will be imparted to the point 96, and a wavy record, 25 as shown in Fig. 17, will be formed in the edge of the film. This same edge can later be used to reproduce the same pitch of tone as that originally imparted to it by passing the film under a suitable electrical pick-up device, which is vi- 30 brated at the same rate as the waves thus formed in the edge of the film A. This device (Fig. 25) is preferably of the voice coil type, somewhat like the recording device of Fig. 6 but of very light construction, so that movement of the voice coil 35 in its magnetic field sets up small electric currents which can be amplified.

To prevent possible damage to the diamond point in case the film were to break or the end of it were to pass the roller 43 (Fig. 7), I have provided a safety device in the form of a finger 40 97 which bears upon the film A, and which forms part of a bell crank which is pivotally mounted at 98. The other end of the bell crank carries a mercury switch 99 which is connected in series 45 with the voice coil. Thus the instant the end of the film no longer supports the finger 97, it will be forced inwardly into the space 43a of Fig. 11, thereby breaking the mercury switch 99 and bringing the voice coil to rest. It can also be connected in such a way as to stop the camera, or it may actuate an alarm or signal to show 50 the end of a film. In order to insure smoothness of operation of the record strip at the point where the recording is done, I have provided the shaft 42 with a fly wheel 42a and prefer to mount the shaft 42 in ball bearings, as shown in Fig. 11.

It is very essential that the film A in passing over the sprocket 35 (Figs. 13 to 16 inclusive) do so as smoothly as possible. Where the film has shrunk, however, particularly in the case of 16 millimeter film, the jerkiness produced by the film slipping as it passes over the sprocket teeth causes an irregular motion of the film which produces a "flutter" in the sound generated, which 60 is very annoying. This is particularly true in the case of the small films for the reason that the distance between the holes in the small film is actually greater than that of the larger film, and this coupled with the fact that the smaller film is traveling at a very much slower rate greatly exaggerates any slight error that might occur in the distance between the holes in the film.

To overcome this difficulty I have cut away the 70 center of the sprocket 35 and mounted therein 75

two spaced adjustable members 100 which are carried by a plunger 101 which rests upon a screw 102. Plates 103 of the same height and curvature as the members 100 are secured to the plunger 101 by means of rivets 104, so that they 5 move up and down together. Facing the members 100 and the plates 103 is a spring-pressed shoe 105 which rests upon the film A and holds it in contact with the plates. Thus it will be seen that by adjusting these plates in and out a point 10 will be reached where the distance between sprocket teeth is equal to the distance between sprocket holes, and the film will pass on and off the sprocket smoothly, and the flutter from this 15 source will be eliminated.

Having made a master record strip which is entirely separate and distinct from the motion picture film with which it is in synchronism, the motion picture film negative is developed and printed in the usual way, after which a sound 20 record from the master record strip is imparted thereto. It will also be apparent that a disk record may be made and used instead of the record strip shown, and the sound record on the disk may be re-recorded on the edge of the motion picture film by driving the disk record and the motion picture film in synchronism in much 25 the same way as that shown in Fig. 20, care being taken to see that the sound and action are properly synchronized.

In this the record strip J made as previously shown and described is fed off a reel 106 and through a suitable electric sound pick-up device 107 of a suitable electrical type, and thence to a reel 108. One or more positive motion picture 30 films K, L, are then each threaded into a recording mechanism of the type shown in Fig. 1, and set in synchronism with the master sound record J. The sound pick-up 107 is then connected with a suitable amplifier 109 and the output current 35 from this is connected to a recording device D of Fig. 1. Synchronous motors then serve to drive the master record strip J and the motion picture films K and L, and since these motors are all connected to the same alternating circuit source 40 they will remain in synchronism so that the sound record on the master record strip J will be transferred to the edge of the films K, L, etc. While only two motion picture films are thus shown in the process of being treated, it will be understood 45 that sound can thus be simultaneously recorded on several of them.

The sound thus recorded on the edge of the motion picture film can be picked up, amplified and reproduced in suitable apparatus, as shown 50 in Fig. 21. In this case the motion picture film M with the sound recorded on its edge is passed through a motion picture projector N, which is driven by means of a suitable motor O. The film then passes to a sound pick-up device P 60 which has two guides 110 and 111 between which the film M passes. A stylus 112 of the reproducing pick-up (Fig. 25) engages the sound record on the edge of the film, and this is connected to suitable electric apparatus so that the motion 65 of the film is transmitted to this apparatus as an undulating electric wave. This is then amplified and passed to a loud speaker in the usual way.

The pick-up as shown in Fig. 25 comprises a stylus 112 having a chisel-edged diamond at its 70 end adapted to bear against the sound record edge of a film A. This stylus is mounted on a thin leaf spring 140a and on a leaf spring or link 140b, both being mounted on an arm of the housing 140 which is hollow and which encloses 75

a magnetizing coil 140^c supplied with direct current from a suitable source. The housing and core 140^d are iron and have an annular air gap in which is placed a small coil 140^e. As this coil 5 moves back and forth in the field thus produced, a pulsating current is generated therein which passes through wires 140^f to an amplifier of any well known type, the amplified current being used to operate a loud speaker. A permanent magnet 10 may be used for this purpose, and the members 140^a and 140^b may be enclosed in the housing.

In passing from the motion picture projector to the sound pick-up device, the film M passes over a sprocket 113 which is carried on a shaft 114

15 (Fig. 22) which is driven by a gear 115 which meshes with an idler 116, the latter meshing with a gear 117 on the sleeve 118. This sleeve carries two arms 119 which connect through suitable springs 120 with pins 121 on a plate 122 which is 20 doweled to a shaft 123. This shaft carries a sprocket 124 around which the film M passes and which serves to draw the film steadily through the sound pick-up owing to the compensating and smoothing action of the springs 120. To further 25 insure steadiness of the sprocket 124 the shaft 123 is provided with a worm wheel 125 which drives a governor 126 which is of the well known fly-ball type used on phonographs to obtain a substantially uniform speed of the turntable. As the 30 weights of the governor which are carried on steel members 127 fly outwardly they force a plate 128 against a shoe 129 which tends to slow up the action. By properly adjusting the distance of the shoe 129 from the rotating plate 128 a very 35 smooth and uniform action of the governor is obtained. Where necessary, the sprocket 124 may be of the compensating type shown in Fig. 13.

In Fig. 21 is also shown a device for properly 40 registering the picture and sound on a film. The projector and sound reproducer are secured to a table 130. For this purpose the projector may be held by screws 131, and a suitable adapter as 45 132 may be used for holding certain types or kinds of bases on the table. In this way the distance between the projector and reproducer may be maintained. In connection with this table I use a loop adjusting device comprising a roller 133 mounted on a lever arm 134 which is pivotally mounted at 135, and carries a pin 136 50 adapted to selectively engage holes 137 in the reproducer. Thus each hole may correspond to one type of projector. By setting the pin 136 in the correct hole and stretching the film over the roller 133, as shown in dotted lines, the correct spacing 55 of the film between the projector and pick-up is obtained. After thus threading it through the projector, the roller 133 is released to the full-line position leaving the loop 138 of the desired length.

60 While I have shown and described but a few embodiments of my invention, it is to be understood that it is capable of many modifications.

Changes, therefore, in the construction and arrangement may be made which do not depart from the spirit and scope of the invention as disclosed in the appended claims.

I claim:

1. Apparatus for recording sound on the edge 5 of a motion picture film comprising a pair of rolls between which the film is passed, means for pressing the rolls together to firmly grip the film, means for supporting one edge of the film, 10 and a vibratory recording tool adapted to engage the opposite edge of the film at the point where it is gripped, said opposite edge slightly overhanging the ends of the rolls.

2. Apparatus for recording sound on the edge 15 of a motion picture film comprising a pair of rolls between which the film is passed, means for pressing the rolls together to firmly grip the film, 20 means for supporting one edge of the film, a vibratory recording tool adapted to engage the opposite edge of the film at the point where it is gripped, said opposite edge slightly overhanging the ends of the rolls, and means in advance of the recording tool for trimming the edge of the film.

3. A sound recording device comprising a metal frame, an iron core extending inwardly from one end, the frame being spaced from the other end to form an annular air gap, a magnet coil about the core for energizing the same, a movable member in axial alignment with the core and mounted in the frame for endwise movement, said member having a disk mounted thereon, a rubber pad on each side of the disk to serve as dampers for the member, the core bearing against one of the pads and being adjustable endwise to vary the damping action, and a recording tool carried by the movable member.

4. Apparatus for recording sound on the edge 40 of a motion picture film comprising a pair of rolls between which the film is passed, means for pressing the rolls together to firmly grip the film, means for supporting one edge of the film, and a vibratory recording tool having a chisel-like edge 45 adapted to lie transversely of the edge of the film and adapted to engage the opposite edge of the film at the point where it is gripped, said opposite edge slightly overhanging the ends of the rolls.

5. Apparatus for recording sound on the edge 50 of a motion picture film comprising a pair of rolls between which the film is passed, means for pressing the rolls together to firmly grip the film, means for supporting one edge of the film, and a vibratory recording tool having a chisel-like edge 55 having a radius of substantially .001" adapted to lie transversely of the edge of the film and adapted to engage the opposite edge of the film at the point where it is gripped, said opposite edge slightly overhanging the ends of the rolls.

JOHN RIPLEY KIEL.
